Primary Examiner — Jack Reickel*Assistant Examiner* — Keith J Wilson(74) *Attorney, Agent, or Firm* — Volpe Koenig**CLAIM**

I claim the ornamental design for a faucet stream straightener, as shown and described.

DESCRIPTION

FIG. 1 is a top plan view of a faucet straightener in accordance with my design;

FIG. 2 is a top, front, left, perspective view thereof;

FIG. 3 is a bottom plan view thereof;

FIG. 4 is a bottom, right, rear perspective view thereof;

FIG. 5 is a front elevational view thereof;

FIG. 6 is a right side elevational view thereof;

FIG. 7 is a left side elevational view thereof; and,

FIG. 8 is a rear elevational view thereof.

The broken lines shown represent unclaimed portions of the faucet stream straightener that form no part of the claimed design.
